UNITED STATES PATENT OFFICE.

IDA WHALEY STRAHAN, OF MONTCLAIR, NEW JERSEY.

HAIR-CURLER.

1,328,771.

Specification of Letters Patent.

Patented Jan. 20, 1920.

Application filed June 24, 1919. Serial No. 306,466.

To all whom it may concern:

Be it known that I, IDA WHALEY STRAHAN, a citizen of the United States, and a resident of Montclair, in the county of Essex and State of New Jersey, have invented a new and Improved Hair-Curler, of which the following is a full, clear, and exact description.

This invention relates to a hair curler, and aims to provide a device of this nature which will curl the hair without the use of heat.

It is a well-known fact that hair on the human head is often destroyed by the use of hair curlers of the hot-iron type, for the reason that the hot iron being firmly pressed into contact with the hair causes the same under any conditions to become extremely dry and brittle, and if the iron is heated slightly over the necessary temperature it will result in the burning of the hair, which will cause an immediate breaking off of the same resulting in splitting the hair and in the ultimate destruction of the roots of the hair.

Another method of curling the hair is by means of wrapping and tying separate strands of hair around individual members, which may take the shape of anything from a piece of paper to specially-constructed clamps. This method is not satisfactory for the reason that each separate strand of hair will have a wave or curl of different depth, so that the finished appearance when the hair is dressed cannot in any way be confused with a natural curl. Besides the above, this method is objectionable for the reason that the user of the same is rendered extremely unsightly for quite a lengthy period, due to the fact that the members in question must remain in place for a comparatively long time. A further objection to this latter method is that the hair strands curled around the individual members form comparatively hard knots, which are extremely uncomfortable, particularly when the wearer lies down to rest.

Having these various objections in mind, I have invented a new and improved form of hair curler which may be used without the slightest injury to the hair to be curled.

A still further object of this invention is the provision of a hair curler by means of which the finished hair will have what is known as a "Marcel wave" over its entire surface.

Another object of the invention is the provision of means by virtue of which the depth of the wave imparted to the hair may be regular.

A still further object of the invention is the provision of a hair curler which, when in place, will not be unsightly or uncomfortable.

Other objects of the invention will become apparent upon a perusal of the specification.

Reference is to be had to the accompanying drawings which illustrate one practical embodiment of my invention, and in which—

Figure 1 is an elevational view of a person using my hair curler;

Fig. 2 is a side elevation similar to Fig. 1 but showing the hair applied to such curler;

Fig. 3 is a sectional view taken through the hair curler; and

Fig. 4 is a section taken along line 4—4 of Fig. 3.

In all of these various views like reference numerals designate similar parts and the reference numeral 1 indicates the hair of the user to whose head my hair curler is applied, including a spirally-extending spring 2 to whose upper surface is applied a cover 3 of cloth, or other suitable material, indicated by the reference numeral 3. Extending parallel and between the convolutions of the spiral spring 2 is a tape, such as indicated by the reference numeral 4, and strips 5, adapted to retain the curler in applied position, having their upper ends attached to the lowermost portion of the spring 2. Adjacent the lowermost portion of the spring 2 and above the same there is provided a 95 circumferentially-extending tape, or draw string, 6 for a purpose hereinafter more fully specified.

In operation it will now be appreciated that primarily the hair is combed straight down over the head of the user in the manner indicated in Fig. 1. The hair curler is then applied to the head and retained in position by means of the straps 5 and the draw string 6. The hair is now folded upwardly along the sides of the covering 3 until it finally assumes the position illustrated in Fig. 2, in which it is retained by means of any suitable device, such as a string 7. The tape 4 is now tied as tightly as may be desired in the form of a spiral which extends between the convolutions of

the spring 2 and through the entire length thereof, thus forcing the hair 1 to conform to the said convolutions.

It will readily be appreciated that after 5 the hair curler is applied to the user's hair for a certain length of time the hair will assume a wave equivalent to the depth of the grooves formed by the tape 4 pressing tightly against the cover 3 between the convolutions of the spring.

It will further be understood that a curl 10 of an acute angle may be produced, according to whether a sufficient tension is exerted upon the tape 4, which would result 15 in a deepening of the groove between the convolutions of the spring. Further, it will be understood that by means of a needle, or other suitable device, the length of the covering as extending in a continuous plane 20 might be varied by stitching the covering so that it would extend more or less around the wire forming the spring.

It will also be understood that any number 25 of variations in structure may be resorted to without in the least departing from the scope of my invention.

Having thus described my invention, I desire to claim:

1. A hair curler including a head encir-

eling cap of flexible material whose outer 30 surface is grooved.

2. A hair curler including a head encir- 35 cling cap of flexible material whose outer surface is grooved, and means associated with said cap for forcing the hair into such groove.

3. A hair curler including a head encir- 40 cling cap formed with a spirally-extending groove in its outer face, and means for forcing the hair into said groove.

4. A hair curler including a head encir- 45 cling cap formed with a grooved outer surface, and a tape adapted to engage the outer face of the hair for forcing the same into such grooved surface.

5. A hair curler including a cap comprising 50 a spiral spring, a covering adapted to envelop such spring, the hair of the user being applied to the outer surface of said covering, and means associated with the cap for forcing the hair into the groove.

6. A hair curler including a head encir- 55 cling cap formed with a grooved outer surface, and a draw string associated with said cap adjacent its lower edge for securing the same in applied position.

IDA WHALEY STRAHAN.
